ALARM LATCH

Felix Gilbert, New York, N.Y., assignor to General
Alarm Corporation, New York, N.Y., a corpora-
tion of Delaware

Filed Oct. 24, 1966, Ser. No. 4,401

Term of patent 14 years

(Cl. D50—5)

Fig. 1

Fig. 3.

Fig. 4.

Fig. 2.

Ti. S.

FIG. 1 is a front elevational view of an alarm latch embodying my new design;

FIG. 2 is a top plan view of said alarm latch;

FIGS. 3 and 4 are side elevational views of said alarm latch; and

FIG. 5 is a cross-sectional view taken horizontally across the face of FIG. 1.

I claim:

The ornamental design for an alarm latch, as shown.
